UNITED STATES PATENT OFFICE

GEORGE E. DICKSON, OF EVANSTON, ILLINOIS

NAIL HEAD CAPPING MACHINE

Application filed December 28, 1928. Serial No. 328,874.

This invention relates to improvements in nail head capping machines and it consists of the matters hereinafter described and more particularly pointed out in the appended 5 claims.

The primary object of the invention is to provide an automatic machine for applying a cap of soft metal to the head of a nail to make the same weather-proof.

Another object of the invention is to provide a machine for this purpose which is fast and positive in its operation and insures uniformity in the finished product.

A further object of the invention is to provide a machine of this kind wherein a pellet like mass of metal softer than that of the nail is compressed about the nail head cold, whereby the amount of such softer metal is reduced to a minimum and waste is thereby avoided.

These objects of the invention as well as others, together with the many advantages thereof will more fully appear as I proceed with my specification:—

In the drawings:—

Fig. 1 is a view in front elevation of a nail head capping machine embodying my invention.

Fig. 2 is a view in side elevation of the same on an enlarged scale.

Fig. 3 is a horizontal sectional view through the machine on a further enlarged scale as taken on the line 3—3 of Fig. 2.

Fig. 4 is a vertical sectional view through the machine as taken on the line 4—4 of Fig. 3.

Fig. 5 is another vertical sectional view through the machine as taken on the line 5—5 of Fig. 3.

Fig. 6 is a detail view on an enlarged scale of parts shown in the lower right hand corner of Fig. 5.

Fig. 7 is a vertical sectional view through a part of the machine as taken on the line 7—7 of Fig. 4.

Fig. 8 is another vertical sectional view as taken on the line 8—8 of Fig. 4.

Fig. 9 is a horizontal detail sectional view on an enlarged scale as taken on the line 9—9 of Fig. 8.

Fig. 10 is a detail view on an enlarged scale

of parts shown in Fig. 4 and which will be more particularly referred to later.

Fig. 11 is a horizontal sectional view through a part of the machine as taken on the line 11—11 of Fig. 8.

55

Fig. 12 is a detail vertical sectional view on an enlarged scale as taken on the line 12—12 of Fig. 3.

Fig. 13 is a detail vertical sectional view on an enlarged scale as taken on the line 13—13 of Fig. 3.

Fig. 14 is another vertical detail sectional view as taken on the line 14—14 of Fig. 13.

Fig. 15 is a perspective view of one of the ejector arms employed in my improved machine and which will be more fully referred to later.

65

Figs. 16 and 17 are detail vertical sectional views as taken on the lines 16—16 and 17—17 respectively of Fig. 11.

70

Fig. 18 is a perspective view of the head end of the nail upon which a soft metal cap is applied by my improved machine.

Fig. 19 is a view of a pellet like mass of soft metal which is compressed while cold, upon the head of the nail shown in Fig. 18 to provide the cap therefor.

75

Fig. 20 is a vertical sectional view through the head end of a nail capped by my improved machine.

80

In general my improved machine comprises a suitable punch press like frame upon the bed of which there is mounted a step by step rotating die carrying plate, the latter being substantially horizontally disposed but pitched or tilted downwardly toward the rear of the machine. In the peripheral margin of said plate is mounted a plurality of die carriers and dies, so disposed that in the

85

step by step rotation thereof, a nail is fed into a number of such dies point down.

When said dies with the nails therein reach the front of the machine, a pellet like mass of softer metal is deposited in each die upon the head of the nail therein and when said dies

90

with the nails and pellets therein reach the rear of the machine, coacting punches descend to compress the pellet upon the head to form the cap. Thereafter as the said dies move

95

away from the punches, in the rotation of

100

the plate, the finished or capped nails are ejected from the dies and are then directed out of the machine into suitable containers or kegs provided therefor.

5 Thus as is apparent, the machine comprises essentially a frame with the step by step rotating die carrying plate and coacting punches, and associated mechanism for feeding nails and pellets of softer metal to 10 the dies in the desired order, together with means for discharging the capped nails from the machine. In describing the invention in detail, the various mechanisms will be set forth in the order above mentioned.

15 Referring now in detail to that embodiment of the invention illustrated in the accompanying drawings, 1 indicates the base of the machine and 2 and 3 indicate the upright right and left hand side frame members respectively, mounted thereon in the manner of the ordinary punch press. Said side frame members have forward extensions 2^a and 3^a respectively at their bottom ends upon which is fixed a bed plate 4 that is tilted downwardly 20 and rearwardly as best shown in Figs. 1 and 4.

In the top end of said side frames is journaled a crank shaft 5 and suitably mounted for reciprocation in guides 6 on said frame members is a cross head 7 actuated by a connecting rod 8 operatively engaged with said crank shaft. On that end of the crank shaft extending beyond the right hand frame member is a loose, belt driven pulley 9 adapted to 30 be operatively connected to and disconnected from said shaft by a suitable clutch 10. This clutch is actuated by a treadle 11 carried by the base and disposed in a manner convenient for the operator whose station is at the front 40 of the machine. On that end of the crank shaft extending beyond the left hand frame member is fixed a cam 12 and a disc carrying a crank pin 13 the purpose of which will appear later.

45 The bed plate 4 is substantially rectangular in plan and rotatively mounted substantially centrally thereof is a circular die carrying plate 14. Fixed in the bed plate is a stub shaft 15 forming the axis about which said plate 14 is rotated and disposed on said shaft above the plate are top and bottom friction discs 16 and 17 respectively, preferably of fiber. On the top end of the stub shaft is mounted a pressure disc 18 and nuts 19 by 50 which the friction of the discs 16 and 17 may be adjusted so that the die carrying plate cannot rotate too freely and is held snugly 55 down upon the bed plate.

In the periphery of the plate 14 is provided 60 a plurality of arcuately spaced notches 14^a and disposed a short distance within said periphery is a plurality of arcuately spaced openings 20—20, each radially enlarged at its bottom end to there provide an annular shoulder 20^a. In each opening 20 is remov-

ably disposed a die block 21 which has a radial shoulder 21^a at its bottom end to engage the shoulder 20^a. The top end of each die block extends a short distance above the carrying plate 14. It is apparent that the die block can only be inserted from the bottom of the carrying plate which rests upon the bed plate. Therefore, at a convenient point in the bed plate, in the die block circle, I provide an opening 22 through which said blocks may be inserted into and removed from the carrying plate. Said opening 22 which is of a diameter slightly larger than the die block is normally closed to that extent preventing said blocks from dropping therethrough by a slide 23 arranged in an undercut groove 23^a in the bed plate 4 as best shown in Fig. 17. When it is necessary to remove a particular die block from the plate 14, said plate is turned to bring the block into register with the opening 22 and the slide is pulled out to clear said opening when said block will drop down through said opening. The die block is replaced through said opening and the slide is then pushed inwardly to partially close said opening. The amount of movement of said slide is limited by the screw and slot arrangement 23^b best shown in Fig. 11.

In each die block is an axial opening 24 of two different diameters to provide an upwardly facing shoulder 24^a in said opening and disposed in said opening is a die 25 with a shoulder 25^a to seat against the shoulder 24^a. Said die has an axial opening 25^b and the top end of the die which is slightly tapered upwardly and outwardly as at 25^c terminates short of the top end of the die block as best shown in Fig. 12. The opening 25^b in the die is of a diameter sufficient to receive the shank 26^a of the nail 26 to be capped. Said nail has the usual flat head 26^b and an annular shoulder 26^c just below the same as best shown in Figs. 12, 18 and 20 and when said shank is disposed in the die opening 25^b the shoulder 26^c rests upon the tapered top surface 25^c of the die and spaces the head a short distance thereabove. The head 26^b of the nail is of a diameter less than that of the top part of the die block opening 24 to leave an annular space about the head when the nail is in place in said die. The nail is of a length greater than that of the die so that the bottom end of the shank depends below the same and to accommodate said depending end of the shank I provide an 110 annular groove 27 in the bed 4. 115

When the nail is in the die, the top end of the die opening, together with the head of the nail provides a pocket into which a relatively small mass of metal may be deposited to be compressed about the nail head to form the cap. This small mass of metal which is softer than the metal of the nail may be of any convenient shape and I find spherical lead pellets or shot such as indicated at 28 in 120 125 130

Fig. 19 are admirably adapted for the purpose.

In the operation of the machine and during the step by step rotation of the plate 14, nails are dropped into a desired number of die blocks at one point and as said die blocks approach a second point, a pellet or shot is deposited in each die block above the nail head so that the die blocks are loaded after which the said dies pass to another point where the pellet or shot is compressed about the nail head to form a cap 29 thereon as shown in Fig. 20, as will soon appear. As illustrated herein, the machine operates upon two nails at a time but as is apparent this number may be increased or decreased without affecting the principle of the invention.

In the step by step rotation of the carrying plate 14 as the loaded die blocks approach the plane in which the cross head 7 reciprocates, they will register with punches 30—30 carried thereby and which as the cross head descends will engage the lead pellets and in connection with the die blocks, will compress said pellets about the nail heads to form the cap before mentioned. To reinforce the bed plate to withstand the pressure imposed thereon by said punches, I provide in said bed plate an anvil block 31 as best shown in Figs. 4 and 12 which block has a groove 31a that registers with the groove 27 in the bed plate.

As before stated the die carrying plate is rotated step by step and means is provided to impart such movement thereto as follows, it being understood of course, that the various operations are carried on in the intervals of rest between such movements and in the desired timed relations.

40 In the top surfaces of the left hand side of the bed plate 4 is provided a forwardly and rearwardly extending groove 32 in which reciprocates a slide bar 33 and to the left hand rear corner of the bed plate is fixed an up-standing bracket 34. Pivoted to said bracket is a bell crank lever 35 one arm 35a of which is connected by a link 36 to the rear end portion of said slide bar. The other arm 35b of said lever has operatively connected thereto the bottom end of an adjustable rod 37 the other end of which is operatively connected to the crank pin 13 before mentioned.

On the slide bar 33 near its front end is pivoted a pawl 38 one end of which is normally urged into engagement with the periphery of the die carrying plate by a spring pressed plunger 39 mounted on the slide bar as best shown in Fig. 3. The first mentioned end of said pawl is adapted to engage in one of the notches 14a in the die carrying plate and as the slide bar 33 moves rearwardly the carrying plate is turned in a clockwise direction through an angle equal to the angle between said notches. As the slide bar moves forwardly said pawl will click

out of the first notch into the next one as is apparent, ready to impart the next movement to said plate.

The die carrying plate is held against undesired movement in either direction by pawls 40 and 41 respectively pivoted upon the bed plate 4 at the rear left and right hand corners thereof as best shown in Fig. 3, each pawl having coacting spring pressed plungers 40a and 41a respectively to urge them against the periphery of said die carrying plate. Each pawl carries a tooth which so engages opposite ends of different notches 14a as to correctly position the dies with respect to coacting mechanism such as for instance the punches 30. The pawl 40 holds the die carrying plate against undesired movement in a clockwise direction and the pawl 41 holds the plate against an undesired movement in counter-clockwise direction. Of course to turn the plate clockwise by means of the pawl 38, the pawl 40 must first be released and this is done by providing a roller 42 on the rear end of the slide bar 33 which in the forward movement thereof engages that end of the pawl that overhangs the slide bar to turn said pawl about its axis to withdraw its tooth from the associated notch 14a in the die carrying plate.

At the right hand side of the bed plate 95 at about its mid portion is fixed a bracket 43 that overhangs the adjacent margin of the die carrying plate. On each side of said bracket is an irregularly shaped casting 44, both fixed to the bracket in any convenient manner. Each casting has its mid portion cut away to provide a chamber 44a in which is located a pair of coacting pivoted nail holding members 45 and 46 normally urged toward each other by springs 47 at the lower end of each casting. Said fingers coact to yieldingly hold a nail 26 fed to it as will later appear, in alignment with but above the die block 21 positioned below each casting as best shown in Fig. 5.

Associated with each casting 44 is a plunger rod 48 aligned with each nail between the yielding fingers 45 and 46, said plunger having a sliding bearing at its bottom end in a bearing sleeve 49 at the top of the casting and both rods are connected together at their top ends by a cross member 50. Said cross member is in turn carried by the bottom end of a member 51 the other end of which is operatively engaged in a sleeve 52 on the outer end of an upwardly and laterally inclined arm 53 carried by the cross head 7. Thus in the downward movement of the cross head 7, the plunger rods 48 each descend and engage the head of the nail which is pushed downwardly and out from between the coacting fingers 45 and 46, which yield laterally to permit this movement of the nail, each nail dropping point down into the open-

ing 26^b in the proper dies within the associated die block.

The nails are fed to and between the yielding fingers 45—46 by means of tubes 54, one associated with each casting 44. The bottom end of each tube is secured in an extension of said casting and the top end of each tube is fixed to a spout 55 associated with means 56 for delivering nails to the tube, point down. In said means is provided a chute 57 to which nails are delivered in a row to hang pendant therefrom, by a rocking hopper 58, pivoted at one end as at 59 to said chute. The other end of said hopper is supported upon the top end of a connecting rod 60 the bottom end of which is connected to a crank pin 61 on a rotating disc 62. The means 56 is supported upon a suitable frame work 63 and associated with said means is a picker mechanism 64 actuated from the crank shaft 5 to remove the bottommost nail from the chute so that it will drop into the spout, down the tube and into position between the yielding fingers 45 and 46.

At the front of the bed plate 4 is secured a forwardly and substantially horizontal supporting bracket 65. In said bracket is formed a longitudinal slot 66 in which an elongated block 67 has a sliding guided movement. Fixed to the bottom of said block so as to be located below the bracket is a roller 68 behind which is engaged the short arm 69 of a lever 70 pivoted as at 71 to the bracket 65. The long arm of said lever is connected by a link 72 to the forward end of the slide bar 33 as best shown in Fig. 3. The forward end of the slide 66 carries a block 73 with a cross pin 74 therein to which the same ends of a pair of springs 75 are connected, the other ends of said springs being connected to upright pins 76—76 on the bracket 65.

It is apparent that the slide bar 66 is moved in the bracket 65 away from the bed plate by the lever 70 and is moved toward said bed plate by the springs 75.

To the top surface of the block 65 is secured a substantially T shaped flat bar 77 having a wider head 78 at one end which normally overhangs the die carrying plate 14 and in said head is a pair of openings 79 spaced a distance apart equal to the distance between adjacent die blocks. The openings in said head are of a diameter sufficient to freely receive a pellet 28 and said head normally engages on a plate 80 fixed on the inner or rear end of the bracket 65. Said plate has openings 81 in that end overhanging the die carrying plate which openings register with the openings in the die blocks. When the bar 77 is in its normally inward position, the openings 79 and 81 register so that such pellets as may be in said openings fall therefrom and through the openings 81 into the

underlying die blocks above the heads of the nails therein.

82 indicates an L shaped block having a horizontally disposed base 83 which is fixed to the inner end of the bracket 65. Said base is cut away as at 82^a to straddle the head 78 and at the same time provide lateral guides for said head. Secured to opposite sides of the block are substantially vertically disposed standards 84—84 the top ends of which are bent laterally and are secured to the bottom wall 85 of a hopper 86 adapted to contain a supply of pellets 28. Extending between the bottom of said hopper and said block is a pair of pellet tubes 87—87, the front bottom ends of which are cut away as at 87^a in line with slots 82^b—82^b in the block 82 whereby the contents of the tube are visible. 88—88 indicate agitator tubes mounted on the top ends of the tubes 87 for reciprocation. Said tubes have sight openings 88^a at the front thereof which line up with similar openings 87^b in the tubes 87 so that the contents of the top ends of the tubes 87 are visible. The tubes 88—88 are secured together at longitudinally spaced points by top and bottom clamping blocks 89 and 90 respectively. An arm 91 fixed to the cross head 7 has its free end disposed in such a manner as to engage the underside of the clamping block 89 so that in the upward movement of the cross head, a like movement is imparted to the clamping block 89 and tubes 88. In the upward movement of said tubes, they force their way through the supply of pellets and agitate them so that some of said pellets are certain to enter the tubes 88 and thus be guided into the tubes 87. In the downward movement of the cross head 7 and arm 91 the tubes 88 descend by gravity and should they stick to the tubes 87 the arm 91 will engage the clamping block 90 and force the tubes 88 downwardly.

When the bar 77 is in its outermost position upon the bracket 65, the openings 79 in the head thereof will register with the bottom ends of the tubes 87 with the result that a pellet 28 is delivered into each of said openings 79 and when said plate moves rearwardly to its innermost position the said pellets are carried therewith to enter and pass through the openings 81 in the plate 80 to be delivered into the die blocks there beneath and on top of the head of each nail therein. Thus for each reciprocation of the bar 77 a pair of pellets is transferred from the bottom ends of the tubes into the die blocks.

Should either a nail or pellet fail to be delivered to the die blocks by the mechanisms above described, certain detector means are automatically brought into play to change the condition of an electric circuit, to notify the operator that one or the other of the above conditions exist and this notification

may be either in the form of a stopping of the machine or the sounding of an alarm or other indicator. However, as the detector mechanism forms no specific part of the 5 present invention it will be only generally described.

On the front end part of the bed plate 4 between the bracket 65 and groove 32 is a block of insulation 92 (see Fig. 3) having 10 spaced contacts 93 thereon. On the arm 91 before mentioned is a bracket 94 from which an arm 95 depends. The bottom end of said 15 arm has pivoted thereto a pair of contact fingers 96 at the outer ends of which are adjustable contact points in the form of screws 97 adapted to register and engage with the contacts 93 under certain conditions. Also carried on each finger 96 is an adjustable stud in the form of a screw 98. These studs 20 are spaced apart a distance equal to the distance between adjacent die blocks and as the cross head 7 descends the fingers 96 together with the screws 97 and 98 will descend with it.

So long as there are nails and pellets in the die blocks the screws 98 will engage upon the pellets in said blocks in the descent of the cross head and will hold the screws 97 out of contact with the contacts 93. However, 30 should a nail or pellet be absent or should the pellet or nail head be undersize, the support normally afforded either screw 98 will be absent in the descent of the cross head with the result that corresponding screw 97 35 will engage the associated contact 93 and thus change the condition in an electric circuit (not shown). This change in condition of said circuit is utilized in this instance to ring a bell 99 to indicate to the operator that something 40 is not as it should be when the operator then stops the machine by throwing out the clutch 10 by stepping on the treadle 11. After matters have been adjusted again by manually supplying the absent nail or pellet, the machine 45 is again started into operation.

After the punch 30 has descended to compress the pellet about a nail head to form the cap thereon, the die holding plate is given another impulse movement and the die blocks 50 with the capped nails therein move into line with means for removing the capped nails from said dies and such means are as follows: In the bed plate 4 on the die block circle and one step or impulse of movement 55 removed from the plane of the punches 30 is located a pair of reciprocating plungers 99-99 best shown in Figs. 13 and 14. The bottom ends of said pair of plungers are fixed to a cross bar 100 carrying a hardened button 60 or stud 101 disposed between said plungers. Said plungers have guided bearing in a block 102 fixed to the under side of the bed plate and extend up through suitable openings 99* in the bed plate. Springs 103 surround the 65 bottom end portions of the plungers between

the cross bar 100 and block 102 and normally urge the plungers downwardly.

To impart an upward movement to said plungers there is provided a rock shaft 104 journaled at its ends in the side arm extensions 2^a and 3^a of the frame below the rear side of the bed plate. Fixed to this shaft is a forwardly extending arm 105 which in the operation of the shaft engages the cross bar button 101 to impart the upward movement 70 to said plungers against the action of said springs 103.

On that end of the rock shaft extending beyond the frame member 3, is fixed a rearwardly extending arm 106 as best shown in 80 Fig. 2. The bottom end of a connecting rod 107 is pivoted to said arm while the top end of said rod is pivoted to an arm 108 mounted on a stub shaft 109 carried by the side frame member 3. Said arm also carries a roller 110 85 disposed in the plane of and adapted to be engaged by the cam 12 on the crank shaft 5. Thus in the rotation of the crank shaft, the cam 12 will engage the roller 110 and through the connecting rod 107 will impart a downward movement to the arm 106 and an upward movement to the arm 105.

As the plunger rods 99 are moved upwardly their top ends will engage the bottom ends of the nails and will push them upwardly so that the caps thereon project a suitable distance above the die blocks. This upward push or movement to the capped nails is imparted in timed relation with the cross head 7 and occurs as said cross head is 90 moving downwardly.

On the bottom surface of the cross head 7, to the right hand side of the plungers 30, is secured a plate 111, which carries two sets of laterally spaced pairs of depending spring fingers 112-112, the top ends of each pair of fingers being secured to opposite sides of associated blocks 113 fixed to said plate. The bottom ends of the fingers of each pair are bent inwardly and upwardly toward each 100 other and are then bent outwardly again as at 114 in Fig. 13.

In the descent of the cross head, each pair of fingers will engage the cap on the nail and will spread or open laterally so as to engage 115 under opposite sides of the cap as best shown in dotted lines in Fig. 13, this gripping upon the cap occurring at that time in which the plungers 99 are at substantially the top of their movement. As the plungers descend 120 and the spring fingers ascend, they will withdraw the capped nails from the die blocks. The next operation is to eject the nails from between the fingers of each pair and this is provided for by means now to be described. 125

115 indicates a block fixed to the under side of the plate 111 midway between the blocks 113 carrying the spring fingers 112. Pivoted on each side of said block 115 is a lever 116 each of which includes a relatively 130

long arm 117 and a downwardly and laterally offset shorter arm 118. The long arms of both levers normally extend downwardly and forwardly into the vicinity of the inner end of the bracket 43 where they are connected together by a bolt 119 as in Fig. 4 and are disposed beneath a roller 120 on the inner end of said bracket. Springs 121 connect said arms to an extension lug 122 (see Fig. 5) on 10 the cross head 7 and normally act to swing said arms upwardly.

The shorter arms 118 are offset laterally to that extent which will position them in planes disposed between fingers 112 of each pair of 15 fingers and in the upward movement of the cross head by reason of the engagement of the long arms with the roller 120, the ends of the shorter arms will engage the cap on the nail held by the associated pair of spring fingers and will eject the same therefrom. This 20 ejection of the nail takes place as the cross head approaches its limit of upward movement when the ejected nail will fall upon an inclined chute 123 provided therefor between 25 the side frame members 2 and 3 respectively to be delivered into a suitable container provided therefor.

From the foregoing description, it is apparent that only a pair of nails is operated 30 upon in successive steps to form the caps thereon but as is apparent this number may be increased or decreased without departing from the spirit of the invention. It is also apparent that for each step or movement 35 of the die carrying plate, a pair of nails is delivered to two die blocks at one point, the pellets supplied thereto at another point, the pellets are compressed upon the nail heads at a third point, and the capped nail is ejected 40 at a fourth point, all of these operations being carried on in succession so that the machine is continuous in its operation.

The machine is automatic in operation and only requires a sufficient supply of nails and 45 pellets to keep it running, and, should either give out, the operator is at once notified as to that condition.

The capped nails produced by my improved machine are far superior to the cast 50 capped nails because less lead is used for each cap, and the caps are more uniform in size and will not become loose on the nail heads either before or after the nails have been driven. Again by compressing the caps 55 in the nail heads, the metal of the cap is rendered more dense which makes them better able to withstand hammering without splitting.

While in describing my invention I have 60 referred in detail to the form, construction and arrangement of the various parts thereof, I do not wish to be limited thereto except as may be pointed out in the appended claims.

I claim as my invention:—

65 1. In a nail head capping machine, a die

adapted to receive and hold a nail during the capping thereof and which nail projects through the bottom of said die, a member engaging the bottom end of the nail for imparting an initial upward movement to said 70 capped nail in removing it from the die and other means for grasping the cap for imparting the final upward movement to the nail for removing it from the die member.

2. In a nail head capping machine, a die 75 adapted to receive and hold a nail during the capping thereof and which nail projects through the bottom of said die, a reciprocating plunger engaging the bottom end of the nail for imparting an initial upward movement to the capped nail in removing it from the die, and other reciprocating means including yielding fingers for grasping the cap and imparting the final upward movement 80 to the nail for removing it from the die. 85

3. In a nail head capping machine, a die adapted to receive and hold a nail during the capping thereof, and which nail projects through the bottom of the die, a member engaging the bottom end of the said nail for 90 imparting an initial upward step in removing the nail from the die, means for grasping the capped end of the nail for imparting the final upward step in removing the nail from the die and means for ejecting the nail from 95 the grasping means.

4. In a nail capping machine in combination with a die member containing a capped nail therein, a reciprocating plunger adapted 100 to engage the bottom of the nail to partially lift the nail from the die and reciprocating means adapted to grasp the cap of the nail to complete the removal of the nail therefrom.

5. In a nail capping machine in combination with a die member containing a capped nail therein, a reciprocating plunger adapted 105 to engage the bottom of the nail to partially lift the nail from the die, reciprocating means including yielding spring fingers adapted to grasp the cap of the nail to complete the removal of the nail therefrom and means for ejecting the nail from said spring fingers. 110

6. In a nail head capping machine in combination with a die member containing a capped nail therein, a plunger spaced from 115 one end of the die member and adapted to engage the bottom end of the nail to partially lift the nail from the die member, and means spaced from the other end of the die member and including a pair of yielding spring fingers movable toward and away from the other end of the die member to grasp the cap of the nail to withdraw said nail from the die member. 120

7. A nail head capping machine embodying 125 therein a support, a step by step movable die member adapted to contain a headed nail and cap material, a cross head reciprocable on said support toward and away from the die member, a punch carried by said cross head 130

to coact with the die member to compress said material about the nail head to form a cap thereon, means carried by the support to partially lift the capped nail from the die member and means also carried by the cross head for grasping the cap of the partially lifted nail to remove the nail from the die member.

8. A nail head capping machine embodying therein a support, a step by step movable die member adapted to contain a headed nail and cap material, a cross head reciprocable on said support toward and away from the die member, a punch carried by said cross head to coact with the die member to compress said material about the nail head to form a cap thereon means carried by the support to partially lift the capped nail from the die member and, a pair of yielding fingers carried by the cross head to grasp the cap of the partially lifted nail to remove the nail from the die member.

9. A nail head capping machine embodying therein a support, a step by step movable die member adapted to contain a headed nail and cap material, a cross head reciprocable on said support toward and away from the die member, a punch carried by said cross head to coact with the die member to compress said material about the nail head to form a cap thereon, means carried by the support for partially lifting the capped nail from the die member, means also carried by the cross head for grasping the cap of the partially lifted nail to remove it from the die member and means for ejecting the capped nail from said last mentioned means.

10. A nail head capping machine embodying therein a support, a step by step movable die member adapted to contain a headed nail and cap material, a cross head reciprocable on said support toward and away from the die member, a punch carried by said cross head to coact with the die member to compress said material about the nail head to form a cap thereon, means carried by the support for partially lifting the capped nail from the die member, yielding fingers also carried by the cross head for grasping the cap of the partially lifted nail to remove it from the die member and means also carried by the cross head and adapted to extend in between said fingers to engage and eject the capped nail therefrom.

11. A nail capping machine embodying therein a support, a step by step rotary plate thereon having a plurality of openings therein, there being an opening in said support with which the openings in the plate are adapted to register, a die member for each opening in said plate and adapted to be inserted into and withdrawn therefrom, through said opening in said support and to engage at one end upon said support, and means for closing said opening to that extent

preventing the withdrawal of said die member therethrough.

12. A nail capping machine embodying therein a support, a step by step rotary plate thereon having a plurality of openings therein, there being an opening in said support with which the openings in the plate are adapted to register, a die member for each opening in said plate and adapted to be inserted into and withdrawn therefrom, through said opening in said support and to engage at one end upon said support, and a plate slidable in the top surface of said support and adapted when in one limit of its movement to extend at least partway across the opening in said support.

In testimony whereof, I have hereunto set my hand, this 19th day of December, 1928.

GEORGE E. DICKSON.
